UNITED STATES PATENT OFFICE.

EDWARD D. GARDNER, OF NEWARK, NEW JERSEY.

DESIGN FOR A BICYCLE HANDLE-BAR GRIP.

SPECIFICATION forming part of Design No. 31,801, dated November 7, 1899.

Application filed September 25, 1899. Serial No. 731,678. Term of patent 7 years.

To all whom it may concern:

Be it known that I, EDWARD D. GARDNER, a citizen of the United States, and a resident of Newark, Essex county, State of New Jersey, 5 have invented and produced a new and original Design for Bicycle Handle-Bar Grips, of which the following is a specification, reference being had to the accompanying drawings, forming part thereof.

- Figure 1 is a plan view of a grip, showing my new design; and Fig. 2 is a longitudinal section taken through the center of the same.

As shown in the drawings, the leading or material feature of my design consists of the 5 cylindrical-shaped grip 1, having a convex exterior surface 2, terminating adjacent to the

opposite ends of the grip in raised annular ribs 3 and 4, with the rib 3 merging into a flat surface 5 at one end of the grip and the rib 4 merging into a tapering surface 6 at the opposite end of the grip, the said surface 6 tapering outwardly from the rib to the edge of the central opening through the grip, as shown. 20

Having thus set forth my invention, what I claim as new, and desire to secure by Letters 25 Patent of the United States, is—

The design for a bicycle handle-bar grip, substantially as herein shown and described.

EDWARD D. GARDNER.
